(57) **CLAIM**

The ornamental design for an x-ray tube, as shown and described.

DESCRIPTION

The patent or application file contains at least one drawing executed in color. Copies of this patent or patent application publication with color drawing(s) will be provided by the Office upon request and payment of the necessary fee.

1. X-ray tube
- 1.1 is a front view;
- 1.2 is a back view;
- 1.3 is a side view;
- 1.4 is a perspective view;
- 1.5 is a perspective view;
- 1.6 is a perspective view;
- 1.7 is a perspective view;
- 1.8 is a top view;
- 1.9 is a bottom view; and
- 1.10 is a side view.
